INTERNAL-COMBUSTION ENGINE.

1,355,451.

Specification of Letters Patent.

Patented Oct. 12, 1920.

Application filed June 19, 1918. Serial No. 240,730.

To all whom it may concern:

Be it known that I, LEE ROYAL CARPENTER, a citizen of the United States, residing at Cleveland, in the county of Cuyahoga, and State of Ohio, have invented a certain new and useful Improvement in Internal-Combustion Engines, of which the following is a full, clear, and exact description, reference being had to the accompanying drawings.

10 This invention relates to internal combustion engines, and particularly to an engine for the propulsion of air craft, although not by any means limited to such use, since it can equally well be used for stationary engine purposes, for automobiles, or for marine use. However in view of certain very marked advantages which it possesses for aerial use, I shall confine my description largely to a specimen engine of this type, but 20 without intent to limit myself thereto.

15 The objects of the invention are the provision of a motor of maximum power and of a minimum weight; the provision of a motor of extremely high efficiency; the provision of a motor which will run equally well at all elevations under all air pressures; the provision of a motor which is susceptible of rapid and inexpensive manufacture; the provision of new and improved controlling and lubricating devices; while further objects and advantages of the invention will become apparent as the description proceeds.

25 In the drawings accompanying and forming a part of this application, I have shown one embodiment of my said invention as designed and contrived for an aeroplane motor, although it will be understood that these drawings are illustrative merely, and do not 30 limit me to the construction and arrangement of details therein shown, which may be varied very widely even for aerial use, to say nothing of other variations possible for marine, stationary, or land vehicle purposes.

35 In these drawings Figure 1 is a rear end view of a complete motor embodying my invention; Fig. 2 represents a side elevation of the motor shown in Fig. 1; Fig. 3 is a horizontal sectional view of the motor shown in 40 Fig. 2; Fig. 4 is a transverse sectional view upon the line 4-4 of Figs. 2, 3, and 7; Fig. 5 is a sectional view on the line 5-5 of Fig. 4; Fig. 6 is a transverse sectional view upon the line 6-6 of Figs. 2, 3, and 7; Fig. 7 is a 45 vertical longitudinal sectional view taken on

the line 7-7 of Figs. 1 and 6; Fig. 8 is a perspective view of the crank bearing; Fig. 9 is a perspective view of one of the pump-outlet valves; Fig. 10 is a perspective view of one of the inlet valves; Fig. 11 is a detail view in longitudinal section of one of the compression cylinders; and Fig. 12 is a detail view in longitudinal section of one of the firing cylinders.

50 In the embodiment of my improved motor herein illustrated the crank case consists of a plurality of similar cylindrical sections, bolted together end to end, each section carrying a plurality of radiating, double acting cylinders, each provided with a double-ended piston connected to the crank by means of wrist pins which project laterally through slots in the sides of the cylinders. In its present form some of these cylinders, preferably all of the cylinders in one section, are 55 compression cylinders which pump the explosive mixture into a single tank, or reservoir, whence it is fed as required to the firing cylinders, each of which is preferably of two 60 cycle type.

55 Describing by reference characters the constructions illustrated in these drawings, 1, 1 represent the elements or sections of the crank case, which are preferably identical cylindrical members of cast aluminum and 65 are formed with angularly spaced flat bosses 2-2 for the reception of the cylinders. In the present embodiment six such bosses are 70 provided for each section, opposite bosses 75 arranged in the same transverse plane, but 80 adjacent bosses being staggered as shown in Fig. 2 so that the cylinders of each section 85 are arranged in three planes, in order that 90 their connecting rods may not interfere.

95 To the opposite ends of the crank case are attached suitable end plates, 5, preferably formed with bracket arms 5^a, of any suitable type, whereby the engine may be supported. The abutting ends of the crank-case-sections are conveniently secured and aligned together by means of rings 6-6, 7-7, the former supporting the ball bearings 8-8, and the latter the sleeve bearings 9-9 in which are journaled the crank shaft 10. This shaft is provided with a number of 100 cranks or throws equal to the number of cylinder-carrying sections; in the present embodiment I have shown three such sections, which is my preferred arrangement, 105 and I have shown the crank-shaft as formed 110

with three throws, 10^a, 10^b, and 10^c. These throws are separated by cylindrical disk portions 11, and each is embraced by a bearing 12, shown in Fig. 10, consisting of a split 5 sleeve having upon its exterior a plurality of pairs of radial ears 13, 14, 15, these ears being spaced angularly about said sleeve in the same way that the cylinders are spaced angularly about the casing section. The exterior 10 of the sleeve is also formed adjacent to the split therein with additional lugs 12^a adapted for the reception of suitable fastening expedients (not shown) whereby the two halves of the same are held together.

15 Each of the cylinders consists of a hollow shell formed at its lower end with a pair of similar, oppositely-projecting, hollow bosses 16—16, the bosses and cylinders being rigidly bolted to the bosses 2—2 of 20 the crank case as shown in Figs. 1, 2, 4, and 5. At its outer end each cylinder is closed by a head 17, and at its inner end by a head 18, while each side wall of the cylinder is formed inside the corresponding boss 16 25 with a longitudinal slot 19. Slidably mounted in each cylinder is a piston 20, traversed by a wrist pin 21 whose ends project through the slots 19—19 where they are articulated to the connecting rods 22, 30 whose opposite ends are articulated to the lugs of the crank-bearing 12. The connecting rods of opposite cylinders are connected to the same lugs, these being the lugs which project perpendicularly to the cylinder axis; 35 and the distance between the lugs being substantially or exactly equal to the length of the wrist pins 21—21, it will be seen that the two connecting rods of each cylinder will at all times be substantially parallel to 40 each other, and nearly in alinement with the corresponding rods of the opposite cylinder.

The cylinders shown are of two kinds, namely, firing cylinders and compression 45 cylinders; and in the arrangement shown, which is a preferable arrangement, the firing cylinders are twelve in number and connected to the end sections of the crank-case, the compression cylinders being six in 50 number and connected to the intermediate section of the crank-case. All the firing cylinders are identical, and are here shown as being of the two cycle, double-acting type, while the compression cylinders are 55 also of the double-acting type.

Each of the firing cylinders is formed at one side, intermediate between the slots 19—19, with a pair of laterally projecting, threaded sockets 25—25 equidistantly 60 spaced from the middle of the cylinder and communicating with a short integral duct 26 having an inlet opening 27. Threaded into each of the sockets 25 is an inlet valve, which preferably comprises an externally 65 threaded barrel 30 formed between its ends

with an annular groove 31 adapted to register with the duct 26, said barrel having a central longitudinal bore slidably receiving the shank 32 of an inlet valve 33 which seats upon one end of the barrel. The barrel is hollowed out underneath the valve head 33 and this cavity communicates with groove 31 by passageways 34, (see Fig. 10). The side of the cylinder opposite the inlet valve is formed with outlet ports 35, here 70 shown as discharging directly into the atmosphere. The exterior of these cylinders is shown as provided with air cooling ribs, although it is obvious that water jackets could equally well be employed; and by the 75 same token it is obvious that a manifold could be employed to receive the exhaust gases and convey them to any desired point of discharge. For igniting the charge each of the heads 17 of the firing cylinders is 80 provided with a spark plug 36, while the inner end of each of those cylinders is formed adjacent to its seat with a lateral boss 37 adapted for the reception of another spark plug 38.

The compression cylinders differ from the firing cylinders only in the arrangement of their valves and manifolds, and in the fact that they have no provision for spark plugs. Each of the compression cylinders is formed 90 at each end with a pair of oppositely-projecting internally-threaded sockets 40—40, projecting at right angles to the wrist pin. Each cylinder is formed at each side with an integral duct 41 opening through the 100 side walls of the corresponding socket so as to place the same in communication with the apertures 42—43, respectively, 42 being the compressor inlet, there is screwed into each of the corresponding sockets 40—40 an 105 inlet valve which is preferably identical with the inlet valve employed in the working cylinders; and the opening 43 being the compressor discharge, there is screwed into the corresponding sockets 40—40 a suitable 110 pump-outlet valve, which differs from the inlet valve in having its seat oppositely arranged. A convenient way of making the same is illustrated in Figs. 9 and 11, wherein 45 represents the hollow valve-barrel at 115 its inner end the seat 46 to which is fitted the head 47 of a puppet valve, whose shank 43 is sleeved in the plug 49 which is threaded inside the barrel 45.

In the present embodiment I have shown 120 a difference between the construction of the pistons in the firing cylinders and those in the compression cylinders; although the same type of piston could if desired be used in both cylinders, or either piston could 125 be used in certain other types of engines with desirable results. Referring particularly to Fig. 4 wherein there is shown in longitudinal section one of the working or firing cylinders together with its piston it 130

will be seen that the piston consists of a pair of concentric cylindrical walls 52 53, joined together at their ends by webs 54, and traversed at their center by the integral sleeve 55 in which is fitted the piston pin 21. Adjacent to each end the outer wall 52 is formed with grooves for the reception of piston rings in accordance with usual practice; and slidably fitted within the two short cylinders 53 are smaller pistons 56, 56 which are normally held in outward position by means of coil springs 57. Complete ejection of the piston 56 is prevented by a suitable removable stop 58 carried by the wall 10 53. The stiffness of the springs 57 is such that the inner piston will be little if any displaced nearing the compression stroke, but will be decidedly depressed at the beginning of the power stroke. This leads to 20 a decided saving in cylinder size, space, and weight, facilitates scavenging, and gives more uniform power stroke, the initial force of the explosion being partly absorbed by the spring and by the gas inside the small 25 cylinder, this force being returned gradually during the power stroke, so that when scavenging occurs there is no pocket to hold burnt gases. In fact the spring is not always found to be essential since the gases 30 beneath the small piston will themselves oppose its depression. This construction affords a high compression with a smaller quantity of charge and employs that charge more evenly throughout the power stroke.

35 The piston in the compression cylinder consists merely of a hollow cylindrical shell 60 having closed flat ends as shown in Fig. 6 and traversed at its middle by an integral sleeve 61 in which is mounted the wrist pin 40 21. Adjacent to each end the wall 60 is grooved for the reception of the usual piston rings. The pistons of the compression cylinders are also longer than those of the firing cylinders, since the latter must necessarily leave some compression space, while in the latter any such space would be highly objectionable.

For cooling the interior of these pistons, both compression and firing, their side walls 50 are formed at points adjacent to the piston pins with apertures 63, 63 arranged to register with the slots 19 as the piston reciprocates, thus permitting a puff of air to pass therethrough. The air employed for this 55 purpose is derived from the interior of the crank case, suitable expedients being provided to secure a continuous rush of air therethrough. In the case of an aeroplane motor it is sufficient to form the forward end 60 plate with apertures 64 (see Fig. 3), the various rings 6 and 7 being similarly formed with apertures 65, up to the last ring or plate which is preferably closed; the rush of air through the casing, consequent upon the bodily movement of the engine and con-

sequent upon the propeller action, will force a constant stream of air through the crank case and out through the bosses 16—16, thus keeping the inner heads 18 cool and simultaneously producing an air flow through the pistons. The outer ends of the bosses 16 are preferably covered by continuation housings 66, suitably apertured to permit the escape of this air. The inrushing air has a further advantage of sweeping around the tank 4 and thus reducing the compression temperature of the same and increasing the weight of the charge introduced 75 into each firing cylinder.

The open character of the crank case 80 clearly renders impossible the employment of a splash system of lubrication, wherefore a directed force feed system is employed whose preferred arrangement is as follows. Each crank section or throw of the shaft 85 is formed with a longitudinal bore 70 communicating with the exterior surface of that portion by means of oil ducts 71. The bores 70 also communicate with grooves 72 formed in the disks 11, which grooves in turn communicate with oil ducts 73 formed in the rings 7—7 and communicating with an oil pipe 74 leading from the oil reservoir 75 (see Fig. 7). Suitable branches 76 lead from this pipe to the various cylinders as 90 shown in Figs. 1, 4, 5, and 6. Propulsion of this oil may be effected in any convenient manner, the simplest mode I have so far conceived being that of connecting the reservoir 75 with the pressure tank 4 by means 100 of a controlled conduit 77 so that the mixture-pressure will force the oil through the system. The connecting rods are preferably lubricated by being made hollow and packed with grease. 105

According to the preferred arrangement the compression cylinders are connected together in pairs by means of arcuate inlet-manifolds 80, 81, and 82 communicating with the inlet openings 42 and each provided 110 with a depending boss 83 adapted for the reception of the carbureters 84, 85, 86, respectively. To the opposite or outlet apertures 43 of the same cylinders are connected the arcuate pressure-manifolds 87 connected 115 to the conduits 88 which lead to the tank 4.

The firing cylinders are even more simply arranged, the apertures 27 being connected to identical arcuate manifolds 89 all of which communicate by means of pipes 90 120 connected to the tank 4.

My engine presents the unique feature that control can be effected either by closing all the carbureters simultaneously, or by completely closing some and leaving others 125 open, thus producing an engine of 8, 16, or 24 cylinders at will.

There being twelve firing cylinders upon the engine here shown, each of said firing cylinders being of double-acting construc- 13

tion and of two-cycle type it will be seen that my present engine will afford the crank shaft twenty four separate impulses to each revolution which is equivalent of a forty-eight cylinder motor of four-cycle type, thus producing a very even and continuous torque, high fuel economy, and large power per unit of engine weight.

Furthermore my engine can be increased in size with very great facility, merely by adding further identical sections and substituting a longer crank-shaft with more throws. Of course a proper balance must be maintained between firing cylinders and compression cylinders and this balance will depend to a considerable extent upon the atmospheric conditions expected. Thus for sea-level use a given number of compression cylinders will feed more firing cylinders than would be permissible for aeroplane use. The arrangement of the two varieties of cylinders is largely a matter of choice, care being taken to preserve the best possible engine balance and to impose a minimum of strain on the crank shaft. I do not confine myself to the constructions and arrangements or the details herein shown, since the same can be modified very markedly without departing from the scope of my inventive idea or sacrificing the benefits of my improvements.

Certain subject matter herein set forth is reserved for subsequent applications, certain of which have already been filed and are identified as follows: Serial No. 259,968, filed Oct. 28, 1918; Serial No. 260,783, filed Nov. 2, 1918.

Having thus described my invention what I claim is:—

1. In an engine, a crank, a plurality of cylinders arranged around said crank, a single bearing member freely journaled on said crank, and paired connecting rods for the different cylinder-pistons, there being two rods articulated to each piston, all of said rods being articulated to said bearing member and said pistons being otherwise independent of each other.

2. In an engine, a crank, alined cylinders located upon opposite sides of said crank, pistons therein, a single bearing member journaled on said crank and having external attaching portions projecting perpendicularly to the axis of the corresponding cylinders, and a pair of connecting rods articulated to each piston and to said attaching portions.

3. In an engine, a crank, alined cylinders located upon opposite sides of said crank, pistons therein, a single bearing member journaled on said crank and having independent external ears projecting perpendicularly to the axis of the corresponding cylinders, and a pair of connecting rods pivoted to each piston and to said ears, the distance between the piston pivots being

equal to that between said ears, whereby said connecting rods may remain parallel to each other at all times.

4. In an engine, a crank bearing adapted to be journaled on a crank and having a plurality of pairs of external ears arranged in successive planes longitudinally of said bearing, successive ears being angularly spaced for attachment to radial cylinders.

5. In an engine, a crank casing comprising a plurality of similar hollow sections joined together end to end, a plurality of cylinders secured to and radiating from each section, and end members for said casing, one at least of which is formed to permit the free ingress of air, the sides of said sections adjacent to the cylinders being formed with apertures permitting the escape of air.

6. In an engine, a crank, a plurality of cylinders arranged around said crank, a single bearing member journaled on said crank, a crank shaft traversing said casing, a bearing located at the joint between each pair of sections, said bearing being formed to permit the movement of air therewith, and end members for the casing, at least one of which is formed to permit the free ingress of air, the sides of the sections being apertured to permit the escape of such air.

7. In an engine, a crank casing comprising a plurality of similar hollow sections joined together end to end, a plurality of double acting cylinders secured to and radiating from each section, said sections having air-escape ports adjacent to the cylinders, and means for causing a flow of cooling air through the casing.

8. In an engine, a fixed casing, a plurality of cylinders radiating equidistantly from said casing, each cylinder having both ends closed and having longitudinal slots in its sides, a piston in each cylinder, a pin traversing each piston and extending through said slots, connecting rods articulated to said pins outside of the cylinders, and a rotatable crank shaft inside said casing to which all said connecting rods are operatively connected.

9. In an engine, a casing, a plurality of double ended two-cycle cylinders secured to and radiating from said casing, each cylinder having longitudinal slots in its sides, a piston in each cylinder, a pin traversing each piston and extending through said slots, connecting rods articulated to said pins outside of the cylinders, a crank-shaft inside said casing to which all said connecting rods are operatively connected, means for passing air through said casing to cool the inner heads of the cylinders, and means other than casing-pressure to feed combustible mixture to the cylinders.

10. In an engine, a casing, a plurality of cylinders secured to and radiating from said

5 casing, each of said cylinders having slotted sides and closed ends, the walls of said cylinders being ribbed for air cooling, a crank in said casing, pistons in said cylinders and 5 operatively connected to said crank by way of the slots, and means for passing air through said casing whereby the inner heads of said cylinders are cooled.

11. In an engine, a casing, a plurality of 10 cylinders secured to and radiating from said casing, each of said cylinders having slotted walls and closed ends, pistons in said cylinders and having air passageways there- 15 through, a crank in said casing and opera- tively connected to said pistons by way of 20 said slots, said air passageways being ar- ranged to register with said slots at different times, and means for passing air through said casing and through said slots and through said piston passageways.

12. In an engine, a plurality of cylinders 25 projecting from a common axis, a crank- shaft journaled along such axis, a sleeve journaled on the crank throw, a piston in each cylinder, and a pair of parallel connecting rods pivoted to each piston and to 30 said sleeve, said rods being arranged in a plane transverse to the crank shaft axis.

13. A crank bearing for engines comprising 35 a split sleeve adapted to surround the crank between its cheeks and having upon its exterior a plurality of lugs arranged thereabout in oppositely projecting pairs, successive pairs of such lugs being spaced at different distances longitudinally of said sleeve.

14. A crank bearing for engines comprising 40 a split sleeve adapted to surround the crank between its cheeks and to extend sub- stantially from end to end thereof, the exte- 45 rior of said sleeve being formed with a plu- rality of sets of oppositely projecting pairs of attaching ears, the various sets being equi- distantly spaced along said sleeve and also equiangularly spaced therearound.

15. In an engine a crank shaft having a 50 plurality of crank throws, a cylindrical por- tion between adjacent throws and concentric with the shaft, the exterior of such cylindri-

cal portion being circumferentially grooved, 50 a sleeve bearing embracing said cylindrical portion and having therein an oil duct com- municating with such groove, each crank throw being formed with oil ducts com- municating with said groove and opening 55 through the crank exterior.

16. In an engine, a crank, aligned cylinders located one on each side of said crank, each cylinder having slotted walls, pistons in said cylinders, piston pins projecting through the 60 slots, a bearing member journaled on said crank and having oppositely projecting external ears arranged transversely of the cylinder axis, and connecting rods articulated to said ears and pins, there being one rod 65 on each side of each cylinder and the rods of opposite cylinders being approximately in alinement.

17. In an engine a pair of opposed cylinders having closed ends and slotted sides, a 70 piston in each cylinder, a piston pin traversing said piston and projecting through the slots, a connecting rod articulated to each end of each pin, and a crank located between said cylinders with its axis perpendicular to 75 said piston pins, both sets of connecting rods being operatively connected to said crank.

18. In an engine, a crank bearing adapted to be journaled on a crank and having a plu- 80 rality of sets of external ears adapted for the reception of connecting rods, there being two rods and two sets of ears for every pis- ton which is connected to said bearing.

19. In an engine, the combination with a 85 crank and a plurality of cylinders presented endwise thereto, of a bearing member journaled on said crank and having external bearings, two for each of said cylinders, said last bearings having their axes parallel to said crank shaft, a piston in each cylinder, 90 and a pair of connecting rods articulated to each piston and to the corresponding external bearings, whereby a line connecting said last bearings will always remain substan- tially perpendicular to the cylinder axis. 95

In testimony whereof, I hereunto affix my signature.

LEE ROYAL CARPENTER.
